UNITED STATES PATENT OFFICE.

GEORGE H. KING, OF KANSAS CITY, MISSOURI, ASSIGNOR TO THE GEORGE H. KING MODERN WINDOW COMPANY, OF PORTLAND, MAINE.

FASTENER FOR THE MEETING-RAILS OF SASHES.

SPECIFICATION forming part of Letters Patent No. 426,388, dated April 22, 1890.

Application filed August 16, 1889. Serial No. 320,919. (No model.)

To all whom it may concern:

Be it known that I, GEORGE H. KING, of Kansas City, in the county of Jackson and State of Missouri, have invented certain new 5 and useful Improvements in Sash-Fasteners; and I do hereby declare the following to be a full, clear, and exact description of the invention, such as will enable others skilled in the art to which it appertains to make and use 10 the same.

My invention relates to an improvement in sash-fasteners, the object being to provide a burglar-proof fastener which will be effectual in excluding dust, cold, and prevent rattling 15 of the sashes.

With this end in view my invention consists in certain novel features of construction and combinations of parts, as will be hereinafter described, and pointed out in the claims.

20 In the accompanying drawings, Figure 1 is a view in perspective of the fastener. Fig. 2 is a detached view of the locking device, showing the inclines and the end of the locking-bolt therein; and Fig. 3 is a modification.

25 A represents a barrel having a broadened or flanged base 1, adapted to rest upon the top meeting-rail of the lower sash, it having holes 2 2 therein to receive screws or similar fastening devices to hold the barrel rigidly in 30 place after the usual manner.

The key-bolt 3 is fitted loosely in the barrel, and on one end is provided with a flat segmental lug 4, which is rounded on its outer edge, and on its opposite edge forms a pair of locking-shoulders 5 5. A slot 6 on one side of the barrel A extends inward in a straight line for a short distance and then extends laterally and slightly backward about half-way across the top of the barrel, forming the 40 incline 7. The knob or button 8 is secured to the bolt in position to travel in this slot, first, by moving forward with the endwise movement of the bolt, and then by a rocking movement, or vice versa, when the windows

45 are unfastened. The button has ribs 7^a on its lower face which engage depressions on the barrel, which keep the fastener from any possible displacement from the outside, although requiring but slight pressure from the 50 inside in moving it. A spiral spring 8^a may

be mounted on the bolt, and by its tensile action exert a constant backward pressure on the bolt, which facilitates its withdrawal from the locking device when turned opposite the slot 6; but this is not an essential element, 55 and I do not wish to be limited to its use.

Locking device 8^b, which consists of a shell with base flanges 9 9, is secured on the lower meeting-rail of the upper sash opposite the barrel A by means of screws or similar devices, which are inserted through the holes 10 10 in the flanges. This shell has a face-plate 11 and sides 12 12, which act as braces to give the required rigidity to the face-plate. The latter is provided with a slot 14, beveled 65 on the outer edge, if need be, to insure the entrance of the bolt in case the sashes should not be exactly together. A pair of oppositely-extending inclines are formed on the inner face of this plate 11, one being located on 70 each side of the slot 14. By means of these inclines the locking is effected, the shoulders 5 5 riding up them as the bolt is turned. In addition to this, the knob or button rides up the incline 7, and between the inclines in the 75 face-plate and the one in the barrel the meeting-rails are drawn tightly together, so that there remains not the slightest space between them for the entrance of air, dust, or the insertion of any tool from the outside for tampering with the fastening, and all rattling of the sashes is absolutely avoided.

The modification is particularly adapted for securing stops to the frames, which frequently becomes desirable, especially in certain styles of frames embodied in other patents. This device consists of a small cup 16, which is sunk into the frame so that its outer flange 17, by which it is held in, is flush with the frame. The bolt is furnished with a 85 handle 18, which turns in the cup. The locking device in this form consists of a plate 90 provided with the opposite inclines.

It is evident that slight changes might be resorted to in the form and arrangement of the several parts described without departing from the spirit and scope of my invention, and hence I do not wish to limit myself to the particular construction herein set forth; but,

Having fully described my invention, what 100

I claim as new, and desire to secure by Letters Patent, is—

1. The combination, with a barrel having a transverse inclining slot therein, and a bolt 5 adapted to slide and turn in the sleeve, of a locking device having a slot therein to receive the end of the bolt, and a pair of oppositely-sloping inclines located on each side of the slot against which the end of the bolt is engaged, substantially as set forth.

2. The combination, with a barrel having a broadened base-flange and a slot therein, the inner end of which extends transversely across the barrel and slightly backward to 15 form an incline, and a sliding bolt in the sleeve having a knob or button which moves in the slot, and a narrow segmental lug on the end, of a locking device consisting of a shell having a slotted face-plate, and oppositely-extending inclines on each side of the slot for the engagement of the lug on the bolt, substantially as set forth.

3. The combination, with a barrel having

depressions thereon and a slot therein, the inner end of which extends transversely 25 across the barrel and slightly backward to form an incline, a bolt in the sleeve having a knob or button which moves in the slot, and the lower face of which is ribbed to engage the depressions on the barrel, said bolt also 30 having a narrow segmental lug on its inner end, and a spring on the bolt adapted to exert a constant outward pressure thereon, of a locking device consisting of a shell having a slotted face-plate, and oppositely-extending 35 inclines on each side of the slot with which the lug on the bolt engages, substantially as set forth.

In testimony whereof I have signed this specification in the presence of two subscribing witnesses.

GEORGE H. KING.
